DESIGN FOR A COOKING STOVE

Albert Zeller, Jr., Detroit, Mich., assignor to
Admiral Corporation, Chicago, Ill.

Application May 2, 1946, Serial No. 129,231

Term of patent 14 years

(Cl. D81—4)

To all whom it may concern:

Be it known that I, Albert Zeller, Jr., a citizen of the United States, residing at Detroit, in the county of Wayne and State of Michigan, have invented a new, original, and ornamental Design for a Cooking Stove, of which the following is a specification, reference being had to the accompanying drawing, forming part thereof, in which:

Fig. 1 is a front perspective view of a cooking stove showing my new design, and

Fig. 2 is a slightly reduced end view thereof, the end not shown being substantially like the end shown.

I claim:

The ornamental design for a cooking stove, as shown and described.

ALBERT ZELLER, JR.
